C. L. GIEBELL

UNDERREAMER

Filed Sept. 18, 1922

UNITED STATES PATENT OFFICE.

CHARLES L. GIEBELL, OF PENNSBORO, WEST VIRGINIA, ASSIGNOR OF ONE-HALF TO
CHARLES L. DUNHAM, OF PENNSBORO, WEST VIRGINIA.

UNDERREAMER.

Application filed September 18, 1922. Serial No. 588,793.

To all whom it may concern:

Be it known that I, CHARLES L. GIEBELL, a citizen of the United States, residing at Pennsboro, in the county of Ritchie and 5 State of West Virginia, have invented certain new and useful Improvements in Underreamers, of which the following is a specification.

My invention relates to certain new and 10 useful improvements in underreamers and the object thereof is to provide a substantial underreamer, in a manner as hereinafter set forth, for enlarging the bore of a well for casing or any other purpose and at any desired point within the well.

Further important objects of the invention are to provide an underreamer which may be readily attached to a string of drilling tools, which is simple in its construction 20 and arrangement, strong, durable and efficient in its use, formed of few parts, readily assembled, and comparatively inexpensive to manufacture.

With the foregoing and other objects in 25 view, which will appear as the description proceeds, the invention resides in the combination and arrangement of parts and in the details of construction as hereinafter described and claimed, it being understood that 30 changes in the precise embodiment of the invention herein disclosed can be made within the scope of what is claimed without departing from the spirit of the invention.

In the drawing forming a portion of this 35 specification and wherein like numerals of reference designate corresponding parts throughout the several views:—

Figure 1 is an elevation of an underreamer in accordance with this invention with portions thereof in section.

Figure 2 is a vertical elevation of the cutter expander.

Figure 3 is a top plan view of cutters in the extended position.

Referring in detail to the drawing 1 denotes the body portion of the underreamer having its lower portion formed with a vertical and centrally disposed stepped bore of four different diameters, comprising the expander-stem bore 2, the spring bore 3, the expander bore 4, and the cutter shank bore 5.

The bores 2, 3, 4 and 5 increase in diameter relatively to each other in the order named and for the purpose to be described. The upper end of the body portion is formed

with threaded portion 1' to permit of its attachment to a drilling stem.

A pair of opposed cutters 6, each provided with a shank 7 at its upper end, and extending into the bore 5, are pivotally connected together by means of the pin 8, which extends through the body portion 1 and through the respective interengaging apertured lugs 9 of the shanks 7. The shanks 7 are pivotally connected adjacent to their lower ends and each has its outer upper end formed with a curved taper 10 for the purpose to be described. The inner face of each of the shanks 7 is flat and inclined outwardly at an angle relatively to the vertical 70 plane of the cutter 6. This construction of the shanks 7 is such that when the cutters 6 are in the expanded position, as shown in Figure 1, the upper ends of the shanks 7 will be in contact with each other, as clearly 75 shown in Figure 3, but when the cutters 6 are contracted the upper ends of the shanks will part or separate as indicated by the dash lines, as at 11.

Slidably mounted for vertical movement 80 in the bores 2, 3 and 4 is the expander element comprising an elongated stem 12 and expander 13. The upper end of the stem 12 extends through the spring bore 3 and into the small bore 2 and is formed with an elongated slot 14 for the passage of a pin 15 carried by the body portion 1. The pin 15 not only limits the downward movement of the expander element and permits of its attached assembly in the body portion 1 independent of the cutters 6, but also prevents rotation of the expander 13 within the bores 85 when in the assembled position.

The lower face of the expander 13 is formed with a recess 16 identical in contour 90 to the upper tapered ends of the shanks 7 when in contact with each other and is adapted to engage the latter for locking the cutters 6 in the expanded position.

A coil spring 17 is mounted on the stem 100 12, having its lower end seated on the expander 13 and its upper end abutting against the shoulder 18 of the bore 3. The function of the spring 17 normally forces the expander 13 downwardly upon the 105 shanks 7.

The expander 13 is further formed with a transverse slot 19 having an upper wall 20 tapering downwardly from the entrance of each side of the slot 19 to its center. 110

The body portion 1 is provided with a pair of diametrically opposed and longitudinally extending grooves 21, the lower end of each of which terminates in a slot 22 which communicates with the expander bore 4 and is in registration with the respective entrances to the slot 19 formed in the expander 13.

An elevating lever 23 is pivotally connected, as at 24, in the upper end of each of the grooves 21. Each of the levers 23 is curved to project from the periphery of the body portion 1, and has its lower end formed with an inwardly extending tapered arm 25 adapted to engage with the tapered upper wall 20 of the slot 19 of the expander 13 for elevating the latter from contact with the shanks 7 when the levers 23 are forced inwardly by contacting with the wall of the well casing, thereby permitting of the contraction of the cutters 6 to also allow their passage through the well casing. The outward movement of the levers 23 is limited by the contour of the recess 26 in which the levers 23 are respectively connected.

It will be noted that the action of the spring 17 will normally force the expander 13 downwardly causing the recess 16 in the lower face thereof to engage the upper ends 30 of the shanks 7 and draw them together thereby forcing the cutters 6 to the expanded position. When drawing the underreamer from a well, the levers 23 upon entering the lower end of the casing will be engaged by 35 the casing wall and forced inwardly causing the arms 25 to engage in the slot 19 and elevate the expander 13 clear of the shanks 7 permitting of the contraction of the cutters 6 and allowing their passage through the casing.

When the underreamer is lowered into a well, the cutters 6 are contracted by manually shifting the levers 23 inwardly to elevate the expander 13, and permit of their insertion into the upper end of the well casing. As soon as the device passes the lower end of the well casing the spring 17 will function to force the levers 23 outwardly and the expander 13 downwardly to engage the shanks 7 and hold the cutters 6 in the expanded or cutting position.

Each of the cutters 6 has its upper end formed with a pair of parallel extending recesses 27. The recesses 27 of one of the cutters 6 are in alignment with the recesses 27 of the other of said cutters 6, when the cutters 6 are in the expanded position. The lower face of the body portion 1 is formed with depending projections (not shown) 55 which engage the respective recesses 27 of the cutters 6 and bear the torsional twist or strain to which the cutters 6 are subjected during the reaming operation which otherwise would be borne by the pin 8 which connects the cutters 6 with the body portion.

The construction of the cutters 6 is such as to provide a clearance 28 between their lower ends and the inner wall of the well casing when cutters 6 are contracted to prevent wear to the said ends and facilitate the downward passage of the reamer through the well casing.

What I claim is:—

1. A reamer comprising a body portion having its lower end provided with a central bore, cutters having shanks extended into said bore, said shanks having interengaging means for pivotally connecting said cutters to the body portion, a spring actuated expander vertically shiftable in said bore and adapted to engage said shanks for expanding said cutters, said expander formed intermediate its ends with a transversely extending opening having one of its walls oppositely bevelled, and means movable towards and pivotally connected at the upper end to said body portion and having the lower end provided with inwardly extending tapered arms engageable in said opening to coat with said bevelled wall to elevate said expander to permit of the contraction of said cutters.

2. A reamer for the purpose set forth comprising in combination, a body portion having its lower end provided with a centrally disposed bore of varying diameters, cutters having shanks extended into said bore, said shanks having interengaging means for pivotally connecting said cutter to said body portion, each of said shanks having its inner face inclined outwardly and its outer upper end formed with a curved taper, an expander provided with a stem mounted in said bore and vertically shiftable therein, the lower face of said expander being recessed and adapted to engage said tapered upper ends of said shanks for expanding the latter, a spring mounted on said stem and normally holding said expander in engagement with said shanks, means engaging said stem to prevent rotation of said expander within said bore, said expander formed with a transverse slot having a depending upper wall, a pair of levers having tapered arms pivotally connected to said body portion, said tapered arms adapted to engage said depending upper wall of said slot for disengaging said expander from said shanks to permit of the contraction of said cutters when said levers are engaged by the inner wall of a well casing on its passage therethrough, the upper portion of said cutters being recessed and adapted to be engaged by depending projections carried by the body portion, substantially as described.

3. A reamer comprising a hollow tubular body having lengthwise extending peripheral grooves terminating at their lower ends in openings, expandable cutters extending into the lower end of said body, a spring

controlled expander element co-operating with said cutters, said element arranged in said body and having its lower portion formed with a transverse opening, and oppositely curved levers mounted in said grooves and having their upper ends pivoted to said body and their lower portions provided with inwardly extending arms operating through the openings in said body and engageable in said transverse opening to elevate said elements to allow for the contraction of the cutters.

4. A reamer comprising expandable cutters, a spring controlled expander element therefor provided with an opening, a support for the cutters and element, and swinging levers, each pivoted at one end to said support and having an inwardly extending arm removed from its other end, said arms extending into said support and engageable

in the ends of said opening to elevate said element to permit of the contraction of the cutters.

5. A reamer comprising expandable cutters, a spring controlled expander element therefor provided with an opening, a support for the cutters and element, and swinging levers, each pivoted at one end to said support and having an inwardly extending arm removed from its other end, said arms extending into said support and engageable in the ends of said opening to elevate said element to permit of the contraction of the cutters, said levers curving in a direction to project from said support and oppositely curved with respect to each other, and said support having means to limit the outward movement of the levers.

In testimony whereof I affix my signature.
CHARLES L. GIEBELL.
